UNITED STATES PATENT OFFICE.

MARC RESEK, OF EAST CLEVELAND, OHIO, ASSIGNOR TO PERFECTION STOVE COMPANY, OF CLEVELAND, OHIO, A CORPORATION OF OHIO.

THERMOSTATICALLY-CONTROLLED WATER-HEATING SYSTEM.

Application filed September 27, 1923. Serial No. 665,243.

My present invention, like that which constitutes the subject matter of a companion application filed by me on the 26th day of September, 1923, Serial No. 664,853 and entitled "Water heating systems" relates particularly to that class of water heating systems used in dwelling houses and such places for supplying hot water for general purposes.

10 The present invention is especially adapted for use in water heating systems that are fired by liquid fuel burners.

The objects of this invention are to provide a water heating system of the class involving a storage tank, a water heater in circulatory communication therewith, and a heating or combustion device, preferably an oil burner, that is supported in operative relation to the circulating element or coil of the water heater and wherein a thermostat is present in the connections leading from the storage tank to the water heater and which has operative connection with the heating device or burner thereby to automatically reduce the heat of the device or burner when the entire contents of the storage tank has been heated to the desired temperature; to provide—in a water heating system of the aforesaid character incorporating an oil burner, preferably of the wick type—a water chamber which is directly associated with or surrounds the burner and through which chamber the water passes as it flows from the storage tank to the circulating element or coil of the water heater, and to place within said chamber, or in such relation thereto as will cause it to be affected by the temperature of the water therein as well as by the temperature of the burner parts, a thermostat having operative connection with the burner whereby the flame of the burner may be reduced, as by turning down the wick, when the entire contents of the tank has been heated to the required degree or when the temperature of the burner parts becomes excessively high.

As to that phase of my present invention which provides for the placing of a thermostat within the connections leading from the storage tank to the water heater, it may be pointed out that this has certain marked advantages over an arrangement whereof I have knowledge and in which a thermostat is included in the connections which lead from the water heater to the storage tank

at the approximate point in the system where the water is the hottest. As a consequence of the thermostat being situated at this point of greatest heat, it is caused to reduce the heat or fire long before the tank is full of hot water; or if adjusted to affect the fire only under a high temperature, so that the contents of the tank may be heated before the thermostat becomes effective, it defeats to a material extent its intended purpose. Furthermore, in such a construction, while adjusted to operate properly under normal conditions, if the fire is turned up unusually high for the purpose of heating the water quickly, as is very frequently done, it causes the thermostat to prematurely operate while the temperature of the water in the tank is still undesirably low. By placing the thermostat in the connections leading from the tank to the water heater, as in my invention, there is the assurance that so long as the burner parts remain at a safe temperature the thermostat will not act to reduce the heat of the heating device or burner until the temperature of the water within the entire system has reached a predetermined degree.

A further object of my present invention is to provide operative connections between the thermostat and wick of such nature as will not interfere with a manual adjustment of the wick at any time.

Further and more general objects are to provide a construction which is comparatively simple, is economical of manufacture, is convenient of installation, and highly efficient and reliable in the accomplishment of the ends in view and which is durable and not likely to get out of order.

To these ends my invention may be defined as consisting of the combination and arrangement of parts set out in the claims annexed hereto and illustrated in the accompanying drawings wherein Fig. 1 represents a water heating system embodying my invention; Fig. 2 is an enlarged side elevation of the water jacketed burner incorporating the thermostatic control, parts being broken away to more clearly illustrate the construction; Fig. 3 is a horizontal section substantially on the line 3—3 of Fig. 2; Fig. 4 is an enlarged sectional detail of a part of the burner and the thermostatic control; and Fig. 5 is a section on the lines 5—5 of Figs. 2 and 4.

105

110

The storage tank, which is shown as an ordinary range boiler, is designated 1, and the water heater is designated 2. The heater includes a circulating element or coil 3 which connects, at its upper end, with a pipe 4, that leads to the top of the storage tank 1, the pipe 4 being shown as connected, through a T 5, with the egress pipe 6 through which hot water is drawn from the 10 tank to various points in the building. The inlet pipe is designated 7 and, in accordance with prevailing practice, leads downwardly through the top of the tank to within a suitable distance of its lower end, as indicated 15 in dotted lines.

The water heater 2 is supported by a stand 10 which sustains an oil burner 11 with its flue or drum 12 in operative relation to the circulating element or coil 3. The burner 11 is of the tubular type and comprises inner and outer wick tubes 15 and 16 respectively. A water jacket 17 partly surrounds the lower end of the burner and it is conveniently formed of a hollow casting having a 25 flange 18 at its upper end into which the outer wick tube 16 of the burner is fitted, the inner cylindrical wall 19 of the jacket constituting, in effect, the lower portion of the outer wick tube. An annular flange 20 that extends inwardly from the lower end of the water jacket is joined to the bottom of the inner wick tube 15 and constitutes the bottom wall of the annular wick space 22 which receives oil from a supply pipe 23 30 through an elbow fitting 24 applied to the lower rear side of the outer wick tube. The oil reservoir from which the supply pipe 23 leads is omitted for clearness.

A tubular wick 25 occupies the wick space 40 and rests at its lower end upon a wick elevator 26 that is connected to the lower end of a rod 27 which occupies a vertical position within a reentrant portion 30 of the inner wick tube 15.

The upper end of the rod 27 is exposed 45 above the top of the portion 30 and has connected to it a rack member 31 that is conveniently in the form of a channel which embraces the reentrant portion 30 and has, in one of its side flanges, a series of slots 50 which effect a rack that is designated 32. The rack member is guided through an opening in a bracket 33 that is secured to the bottom of the burner and within vertical branches 34 and 35 of which is journaled the wick adjusting spindle 36. A pinion 37 is secured to the spindle and meshes with the rack 32. From this it will be seen that when the spindle is rotated in 55 opposite directions it will reciprocate the rack member 31 and likewise the rod 27, thereby to raise and lower the wick 25.

A cylindrical casing 40 is shown as formed integral with the water jacket 17 and as 60 situated within the front portion thereof,

said casing opening outwardly through the front wall of the water jacket and being internally threaded at its outer end for the reception of a screw plug 42. A thermostat 43 is contained within the casing 40 and has at one end a stud 44 that is positioned within a hollow boss 45, formed at the inner end of the casing, and a stem 46 projects from the opposite or forward end of the thermostat through a bore in the plug 42 70 and is secured against turning with respect to said plug by a key 47, the stem being free to slide. The thermostat 43 is in the nature of a metal bellows which contains a fluid that is readily responsive to temperature changes, the fluid expanding under heat and elongating the bellows thereby to project the stem 46. A head 50 is pinned or otherwise secured to the outer end of the stem 46 and it contains a vertical bore 51 75 within which a plunger 52 is reciprocably supported, the upper end of the plunger being reduced in diameter and extended through the reduced upper end of the bore. The plunger is shown as held against turning with respect to the head 50 by means of a pin 53 which projects outwardly from the plunger through a slot 54 in the head. The lower end of the bore 51 is closed by a screw 55 between the inner end of which 80 and the plunger 52 is compressed a spring 56, the spring tending to maintain the plunger 52 in its extreme upward position.

The outer end of the wick adjusting spindle 36 is provided with the usual hand wheel 60, and inwardly of the hand wheel a hub portion of the disk 61 is secured to the spindle, as by means of a pin 62. An annular friction shoe 63 is secured to the peripheral portion of the disk 61, as by rivets 64. A pressure plate 65, rotatably mounted upon the spindle is urged into frictional engagement with the shoe 63 by a spring 66 that is compressed between said plate and an opposed part 67 of a bracket 68 that extends 105 forwardly and thence upwardly from the branch 34 of the previously mentioned bracket 33. The parallel branches 34 and 69 of the respective brackets 33 and 68 are disposed on opposite sides of a cross member 70 of the stand 10 and are secured thereto as by one or more bolts 71. The spring 66 is coiled about a sleeve 73 which has its outer end secured, as by rivets 74, to the pressure plate 65, and the outer end 75 of the spring is engaged through an aperture in the pressure plate 65 while its opposite end 76 is engaged through an aperture in the portion 67 of the bracket 68. The spring 110 is so wound as to cause it to rotate the pressure plate 65 in a counter-clockwise direction (when the parts are viewed from the front), in addition to maintaining the pressure plate with the desired degree of friction 115 against the friction shoe 63. The upper end 120 of the pressure plate 65 is secured to the stand 10 by rivets 77. The wick adjusting spindle 36 is secured to the stand 10 by rivets 78. The wick 25 is supported by the spindle 36 and the burner 11 is supported by the stand 10.

of an extension 77 of the pressure plate is turned rearwardly over the head 50 and carries a pin 79 for cooperating with the previously mentioned plunger 52. From Fig. 5 it will be seen that the adjacent ends of the plunger 52 and pin 79 are formed so as to engage each other in the manner of a pawl and ratchet, the holding faces of the two parts being straight while their outer surfaces are inclined to facilitate engagement of the parts when setting the mechanism, the plunger being forced inwardly during such operation by the cam action of the pin 79 as will be readily understood. A handle 80 is shown applied to the extension 77 to facilitate the setting of the parts.

Under normal conditions the parts are in substantially the positions shown in the drawings with the pin 79 engaged with the plunger 52 so that the pressure plate is held with its extension 77 vertical and the spring 66 under tension, it being remembered that the spring is at all times under sufficient compression to urge the pressure plate 65 against the friction shoe 63 with enough force to cause the rotation of the pressure plate to be transmitted to the spindle 36 through the disk 61, the parts thus constituting a friction clutch between the spindle and the friction plate. The friction is not so great however as to prevent an operator from turning the spindle 36 as by means of the hand wheel 60 independently of the pressure plate for the purpose of adjusting the wick to regulate the fire. With the parts set as shown in the drawings the fire remains substantially constant. As the water within the circulating element or coil 3 is heated it will rise through the pipe 4 and enter the storage tank 1 gradually displacing cold or cooler water from the bottom of the tank through a pipe 85 which has connection with the lower portion of the near branch of the water jacket 17, considering the parts as viewed in the drawings, and after passing through the jacket 17 the water departs through a pipe 86 which is connected with the upper far side of the jacket and leads to the bottom of the circulating element or coil 3.

The circulation thus created continues until the water which passes from the lower end of the tank through the pipe 85 to the water jacket 17 is hot enough to cause the thermostat 43 to be elongated sufficiently to remove the plunger 52 out of engagement with the pin 79, causing the pressure plate 65 to be released and permitting the spring 66 to rotate it in a counter-clockwise direction, or in the direction indicated by the arrow in Fig. 5. This movement of the pressure plate will be transmitted through the friction shoe 63 and disk 61 to the spindle 36 and thence through the connections al-

ready described to the wick, lowering the wick into the wick tubes and thereby extinguishing the flame.

After the water has cooled sufficiently, or hot water has been withdrawn from the tank to permit entrance of additional cold water which shall be practically immediately transmitted to the water jacket 17, the thermostat 43 will be caused to contract, moving the plunger 52 again into the path of the pin 79 after which the pressure plate may be restored to its former position by means of the handle 80 in which position it will be held by the engagement of the pin 79 with the plunger 52. This should elevate the wick to burning position but if through the above performance the wick has been thrown out of adjustment with respect to the pressure plate it may be elevated to the required height by means of the hand wheel 80.

I have described the thermostat as it would function under the influence of the temperature of the water. Additional to this, should the burner parts become overheated, the heat thereof will be transmitted to the thermostat, causing the action above described and the lowering of the wick. By inspecting the construction as illustrated in Figs. 3 and 4, it will be seen how intimately the thermostat and outer wick tube are connected and it is obvious that should the inner wick tube become overheated, which is the part that usually overheats first, the temperature thereof will be transmitted to the thermostat both through its metallic connection therewith and through the intervening body of oil that is present within the wick space 22.

It will be seen, therefore, that my invention provides a contrivance which will automatically reduce or extinguish the heat or fire when the water within the system has reached a predetermined degree of temperature or when the burner parts become overheated, thus insuring against fire hazards or damage to the apparatus from an overheated condition of either the water or the burner parts. It may also be explained that the presence of the water in the water jacket tends to maintain the burner parts relatively cool and thus materially reduces the liability of fires.

Having thus described my invention, what I claim is:

1. In a water heating system involving a storage tank and a water heater in communication therewith, said water heater incorporating a liquid fuel burner by which the water heater is fired and a water chamber in close proximity to the burner, said chamber being in the connections leading from the storage tank to the water heater, a thermostat so situated as to be operated by the temperature of the water in said connections

when the same reaches a predetermined degree or by the temperature of the burner parts when the same becomes excessively high, and operative connections through which the thermostat acts to reduce the heat of the burner.

2. In a water heating system involving a storage tank, and a water heater in circulation therewith, said water heater incorporating a liquid fuel burner of the wick type and a water chamber in close proximity to the burner, said chamber being in the connections leading from the storage tank to the water heater, a thermostat so situated as to be operated by the temperature of the water in said chamber when the same reaches a predetermined degree, or the temperature of the burner parts when the same becomes excessively high, and operative connections between the thermostat and the wick of the burner through which the thermostat acts to lower the wick.

3. In a water heating system involving a storage tank, and a water heater in circulation therewith, said water heater incorporating a liquid fuel burner that is provided with a water jacket included within the connections leading from the storage tank to the water heater so that the water will be circulated through said jacket, a thermostat within said water jacket, and operative connections through which the thermostat acts to reduce the heat of the burner.

4. In a water heating system, in combination, a storage tank, a water heater, a liquid fuel burner of the wick type for firing the water heater, a water jacket incorporated in the burner, communicative connections leading from the top of the water heater to the storage tank, similar connections leading from the lower end of the storage tank to the lower end of the water jacket, and further connections of a similar nature leading from the top of the water jacket to the bottom of the water heater, a thermostat subjected to the temperature of the water in the water jacket, and operative connections through which the thermostat acts to reduce the heat of the burner.

5. In a water heating system, in combination, a storage tank, a water heater, a liquid fuel burner of the wick type for firing the water heater, a water jacket incorporated in the burner, communicative connections leading from the top of the water heater to the storage tank, similar connections leading from the lower end of the storage tank, through the water jacket, to the bottom of the water heater, a thermostat subjected to the temperature of the water in the water jacket, means for raising and lowering the wick of the burner, and operative connections between the thermostat and said means, said connections including mechanism whereby the means may be operated to raise and

lower the wick independently of the thermostat.

6. In a water heating system, in combination, a storage tank, a water heater, a liquid fuel burner of the wick type for firing the water heater, a water jacket incorporated in the burner, communicative connections leading from the top of the water heater to the storage tank, similar connections leading from the lower end of the storage tank to the lower end of the water jacket, and further connections of a similar nature leading from the top of the water jacket to the bottom of the water heater, a thermostat subjected to the temperature of the water in the water jacket, means for raising and lowering the wick of the burner, and operative connections between the thermostat and said means, said connections including a friction clutch whereby the means may be operated to raise and lower the wick independently of the thermostat.

7. In a water heating system involving a storage tank and a water heater in circulation therewith, said water heater incorporating a liquid fuel burner of the wick type, a thermostat subjected to the temperature of the water within the connections leading from the tank to the water heater, a spindle rotatably supported and operatively connected to the wick so that the wick may be raised and lowered by turning the spindle, and operative connections between the thermostat and the spindle, said connections involving a friction clutch through which the thermostat acts to rotate the spindle in a direction to lower the wick when the water within the aforesaid connections rises to a predetermined degree and whereby the spindle may be rotated to adjust the wick independently of the thermostat.

8. In a water heating system involving a storage tank and a water heater in circulation therewith, said water heater incorporating a liquid fuel burner of the wick type, a thermostat subjected to the temperature of the water within the connections leading from the tank to the water heater, a spindle rotatably supported and operatively connected to the wick so that the wick may be raised and lowered by turning the spindle, a member secured to the spindle, a friction plate rotatably supported upon the axis of the spindle adjacent said member, a spring pressing said friction plate against said member and tending to rotate said plate and through it the spindle in a direction to lower the wick, and separable connections between the thermostat and said pressure plate for normally retaining said pressure plate in a given position, said connections being rendered ineffective through the action of the thermostat.

9. In a water heating system involving a storage tank and a water heater in circula-

tion therewith, said water heater incorporating a liquid fuel burner of the wick type, a thermostat subjected to the temperature of the water within the connections leading 5 from the tank to the water heater, a spindle rotatably supported and operatively connected to the wick so that the wick may be raised and lowered by turning the spindle, a member secured to the spindle, a pressure 10 plate rotatably supported upon the axis of the spindle adjacent said member, means acting to press said plate against said member and to rotate said member and through it the spindle in a direction to lower the wick, a head movably supported and connected to the thermostat, separable connections 15 between the pressure plate and said head whereby the pressure plate is held in a given position when the head is in normal 20 position, the head being moved to release the pressure plate when the thermostat is caused to operate by a rise in temperature of the water in the aforesaid connections to a predetermined degree.

25 10. In a water heater of the circulating type incorporating a liquid fuel burner by which the water heater is fired and a water chamber in heat receiving relation to the body of the burner but below the burner 30 flame and that is in circulatory communication with the circulating element of the heater, a thermostat subjected to the temperature of the water in said chamber, and operative connections through which the 35 thermostat acts to reduce the heat of the burner.

40 11. In a water heating system, the combination of a water container, a liquid fuel burner of the wick type in operative relation to the water container, a thermostat so situated as to be affected by the temperature of the water in the system or by the tem-

perature of the burner parts, and operative connections between the thermostat and the wick of the burner through which the thermostat acts to lower the wick when the temperature of the water within the system or the temperature of the burner parts becomes excessively high.

45 12. In a water heating system, the combination of a water container, a liquid fuel burner of the wick type in operative relation to the water container, means for raising and lowering the wick, a thermostat so situated as to be affected by the temperature 50 of the water within the system, and operative connection between the thermostat and the aforesaid means through which said thermostat operates said means to lower the wick when the temperature of the water 55 within the system rises to a predetermined degree, said connections permitting adjustment of the wick through the aforesaid means independently of the thermostat.

60 13. In a water heating system, the combination of a water container, a liquid fuel burner of the wick type in operative relation to the water container, means for raising and lowering the wick, a thermostat so situated as to be affected by the temperature 65 of the water within the system, or by the temperature of the burner parts, and operative connection between the thermostat and the aforesaid means through which said thermostat operates said means to lower the 70 wick when the temperature of the water within the system or the temperature of the burner parts becomes excessively high, said connections permitting adjustment of the wick through the aforesaid means independently of the thermostat.

75 14. In testimony whereof, I hereunto affix my signature.

MARC RESEK.
